United States Patent Office

Des. 190,281
Patented May 9, 1961

190,281

CHAIR

Hanford G. Sher, St. Louis, Mo., assignor to Contour Chair-Lounge Company, Inc., St. Louis, Mo., a corporation of Missouri

Filed Apr. 6, 1959, Ser. No. 55,373

Term of patent 14 years

(Cl. D15—11)

I claim:

The ornamental design for a chair, as shown.
